Primary Examiner — Richard Kearney*Assistant Examiner* — Kendra L Hebel(74) *Attorney, Agent, or Firm* — Jose Cherson Weissbrot(57) **CLAIM**

The ornamental design for a shredder, as shown and described.

DESCRIPTION

FIG. 1 is a perspective view of a shredder, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a perspective view thereof, shown in a condition of use.

All the broken lines in the drawings depict portions of the shredder that form no part of the claimed design.

1 Claim, 8 Drawing Sheets(56)
